GAS BURNER

Filed June 25, 1928

UNITED STATES PATENT OFFICE

FRANK J. C. BLUHM, OF CHICAGO, ILLINOIS, ASSIGNOR OF ONE-HALF TO WILLIAM C. KLEINER, OF CHICAGO, ILLINOIS

GAS BURNER

Application filed June 25, 1928. Serial No. 288,053.

The invention relates to gas burners, and its primary object is to provide an improved burner which is adapted to produce an intense flame for heating purposes with efficient combustion.

The invention consists in the several novel features hereinafter set forth and more particularly defined by claims at the conclusion hereof.

In the drawings which accompany and form a part of this specification or disclosure and in which like numerals of reference denote corresponding parts throughout the several views: Fig. 1 is a section of a burner embodying the preferred form of the invention. Fig. 2 is a transverse section taken on the line 2—2 of Fig. 1. Fig. 3 is a view showing a modified form of the invention.

The invention is exemplified in a burner comprising a vertical pipe-section 4, the lower end of which is connected to a pipe elbow which is connected to a supply pipe 6. This pipe 6 is provided with a control valve 7, and is connected to receive gas under pressure from any suitable source. A plug 8 is threaded into the upper end of pipe 4, and is provided with a small jet opening 9 which is adapted to project the gas upwardly in a slightly divergent column into the atmosphere. The pipe-section 4 is closed, so that the gas projected from the jet will be undiluted with air when it leaves the jet.

The invention contemplates the use of means spaced from the jet to baffle or disrupt the gas-stream at a point properly spaced from the jet to facilitate and produce proper combustion. In Fig. 1 this means consists of a pilot-flame 10. A small pipe 11 is connected to receive gas, preferably from the same source from which the pipe 6 is supplied. Pipe 11 is bowed outwardly, as 11^a, and its upper end is extended to discharge the gas in a horizontal direction into the stream from the jet 9. The flame 10 intersects the stream of gas from the jet 9 and affords sufficient interference to slightly baffle or check the stream of gas from the jet to facilitate and produce efficient combustion, but still leaving sufficient force in the stream to produce an intense flame for heating. When the

gas is cut off from the jet 9, the flame 10 will be continued so that it will also serve as a pilot to ignite the stream from the jet 9. Pipe 11 is fixed in a plug 12 which is screw-threaded into a fitting 13 which is formed with a split clamping collar 13^a to fit around pipe 4. A screw 13^b is adapted to clamp fitting 13 on pipe 4, so the pilot-pipe 11, carried by the fitting 13, can be vertically adjusted to position the pilot to baffle the gas stream at points differently spaced from the jet-plug to effect efficient combustion. A flexible pipe 14 connects the fitting 13 with a pipe 17 connected to the source of gas supply, and permits vertical adjustment of the fitting. A valve 16 is usually included in the pipe 14 to control the pilot flame.

In the modification exhibited in Fig. 3, a porcelain pin 16 is supported in the end of a pipe 17 which is supported from the fitting 4 in any suitable manner. This pin intersects the stream from the jet 9 to produce sufficient interruption of the gas to cause it to burn a short distance from the pin, while still leaving the stream so it will be projected with force a considerable distance. As a result, the burner will produce an intense flame adapted for heating purposes.

The invention exemplifies a gas burner in which the gas is projected into atmosphere in a forcible stream before the gas is mixed with air and with means for checking the pressure sufficiently to produce efficient combustion and an intense flame adapted for heating purposes. The invention also exemplifies a burner of this character in which the means for checking or retarding the stream consists of a small flame of gas which may be utilized as a pilot flame to ignite the gas from the burner.

In practice it has been found that a small jet of gas projected under full pressure and before air is mixed with it and with the pilot-jet disposed several inches from the jet-plug will produce an intense somewhat concentrated flame approximately one foot high, the flame commencing at a point a slight distance above the pilot-jet. The effect of the pilot jet is to heat the gas, as well as to retard it, preparatory to combustion.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In a gas burner, the combination of a pipe adapted to receive gas under pressure, a jet connected to the pipe so as to receive gas therefrom before it is mixed with air and adapted to project the gas into the atmosphere in a stream, a split clamping collar mounted slidably on the pipe, a pilot-pipe connected to the collar and arranged to project a flame across the stream to retard the latter and facilitate combustion, and means for supplying gas to the pilot-pipe, comprising a flexible pipe between and connecting the gas-pipe and the collar.

2. In a gas burner, the combination of a pipe adapted to receive gas under pressure, a jet connected to the pipe so as to receive gas therefrom before it is mixed with air and adapted to project the gas into the atmosphere in a stream, a fitting mounted slidably on the pipe and having a duct extending therethrough, a pilot pipe connected to the fitting so that it communicates with one end of the duct and arranged to project a flame across the stream to retard the latter and facilitate combustion, and means for supplying gas to the pilot pipe comprising a flexible pipe connected to the fitting and extending between the other end of the duct and the gas pipe.

Signed at Chicago, Illinois, this 11th day of June, 1928.

FRANK J. C. BLUHM.
